INVENTOR.

John R. Harris,
By Edward O. Lawrence,
his ATTORNEY.

UNITED STATES PATENT OFFICE.

JOHN R. HARRIS, OF CRAFTON, PENNSYLVANIA.

INSULATOR.

1,079,239.

Specification of Letters Patent. Patented Nov. 18, 1913.

Application filed December 18, 1912. Serial No. 736,975.

To all whom it may concern:

Be it known that I, JOHN R. HARRIS, a citizen of the United States, and residing in the borough of Crafton, in the county of Allegheny and State of Pennsylvania, have invented or discovered new and useful Improvements in Insulators, of which the following is a specification.

My invention consists of a new and useful improvement in split insulators or two-part electrical wiring knobs.

Split insulators are preferred for wiring but their use is attended by numerous disadvantages. The bases and caps are shipped together in bulk and must be sorted out and matched before use. In installing, the base, cap and wire are held together against the wall or other support while the nail is inserted and driven home. The loss through breakage and spalling in shipment, and the loss of time and inconvenience in sorting and installing are very great.

In my present invention the base and cap are connected together by a tube of tough, not easily broken material inserted in the nail bores of the said base and cap and whose ends are upset to prevent withdrawal. Sufficient looseness is provided so that the base and cap may be separated sufficiently to introduce the wire and when the base and cap are driven snugly together to clamp the wire, as when nailed to the wall, the excess length of the tube is accommodated in the countersunk portion of the base. The insulator is secured in place by means of a nail or screw inserted through the tube.

In the accompanying drawings, Figure 1 is a longitudinal section of one of my insulators installed; Fig. 2 is a similar view of the insulator with the base and cap extended; Fig. 3 is an end elevation of the insulator, looking downwardly in Fig. 2; Fig. 4 is an elevation of the interlocking tube, and Fig. 5 is a perspective of the insulator with the base and cap snugly together.

The following is a detailed description of the drawings:

A and B are respectively, the base and cap of a split insulator. The particular design of these elements is not important as my invention may be applied to any split insulator having an axial nail bore.

In the base A, 1 is the axial nail bore end-

ing in the usual countersinking 2, and 3 is the axial nail bore of the cap B.

C is a tube, which may be of metal but is preferably of fiber or other insulating material, inserted through the bores 1 and 3 and having its ends upset outwardly to prevent accidental withdrawal. As shown in Fig. 1, said tube C is of greater length than the combined length of bores 1 and 3, so that when the base A and cap B are together to clamp the wire D, the excess length of tube C extends into the countersinking 2 of base A. This permits the cap to be raised or separated somewhat from the base, as in Fig. 2, to permit the insertion of the wire D.

In installing the insulator, the wire D is laid in the usual clamping groove 4 and a nail or screw E inserted through the tube C and driven into the wall or other support F, the head of the nail and of the tube seating in the usual countersunk outer end of the bore 3 of the cap B. It is thus evident that the bases and caps may be matched and the interlocking tubes installed at the factory or by dealers, thus saving much time and labor and avoiding the breakage and spalling which attends shipment in loose bulk. The tubes being of substantial material are not broken in shipment or handling, and the time required in installing the insulators is greatly reduced. Since my interlocking tubes may be used with any split insulator having an axial bore, the former may be supplied to dealers for assembling insulators in stock.

What I desire to claim is—

The combination, with a split insulator, comprising a base and a cap, having an axial bore, said base having a countersunk portion in its bottom, of a tube loosely disposed in said bore and normally projecting into said countersunk portion, and having a limited longitudinal movement in said bore sufficient to permit separation of the cap and base for the insertion of a wire, and having its ends upset, preventing withdrawal from said bore.

Signed at Pittsburgh, Pa., this 14th day of December, 1912.

JOHN R. HARRIS.
